FURNACE

Ireneus Basil Holtz, Ashville, Pa.

Application February 10, 1938, Serial No. 189,859

7 Claims. (Cl. 122—135)

This invention relates to furnaces of the hot water, steam or vapor type.

In conventional furnaces of the round or square type the hot fuel and the hot gases of combustion cannot transmit the heat units to the side walls very effectively so that the greater portion of the heat units must be dispensed through the upper regions of the furnace to the heating fluid which is circulated in the boiler whereby too great a quantity of the heat units are lost in the flue and chimney.

It is an object of the present invention to provide an elongated furnace which is substantially triangular in horizontal section with a relatively deep firebox so that the heat units are not only transmitted to the heating fluid in headers or coils which form a tortuous path for the hot gases of combustion but are also transmitted to the fluid along the extended side walls of the furnace whereby a maximum utilization of the B. t. u.'s is had.

Another object of the invention is the provision of a furnace which is substantially triangular in horizontal section and which has a hollow dome in communication with a header suspended below the dome to provide a tortuous path for the hot gases of combustion not only below the header but around the longitudinal side edges thereof and also above the header, the suspending means for the header being hollow for placing the dome in communication with the header while the suspending means provides an elongated discharge channel for the hot gases of combustion and this channel is connected to the flue, hollow members extending from the side walls of the elongated furnace and having their inner ends spaced from each other to provide a restricted passage for the hot gases of combustion from the firebox to an elongated flat passage below the header, said members being in communication with the dome and with coils forming the side walls of the furnace to not only provide for a continuous and complete circulation of the fluid but to provide for a maximum heating surface in the furnace.

A still further object of the invention is the provision of a furnace which is substantially triangular in cross section in which a plurality of heating units are spaced from each other to provide a tortuous path for the hot gases of combustion from the firebox so that the gases will travel at times from one end of the furnace to the other before they are discharged in the usual flue, the top of the firebox including a pair of elongated members extending from the side walls

of the furnace towards each other with their inner ends spaced from each other to provide a restricted passage for the escape of hot gases from the firebox, said passage being progressively expanded from the front end to the rear end of the furnace.

This invention will be best understood from a consideration of the following detailed description, in view of the accompanying drawing forming a part of the specification; nevertheless, it is to be understood that the invention is not confined to the disclosure, being susceptible of such changes and modifications as define no material departure from the salient features of the invention as expressed in the appended claims.

In the drawing:

Figure 1 is a vertical section taken along the line 1—1 of Fig. 2.

Figure 2 is a horizontal section taken along the line 2—2 of Fig. 1, and

Figure 3 is a vertical longitudinal section taken along the line 3—3 of Fig. 1.

Referring more particularly to the drawing, 10 designates generally a shell or housing of the furnace which is formed in sections, as shown at 11 in Figs. 2 and 3 and these sections are connected together throughout the length of the furnace in the usual manner by the well known form of conventional nipples although such nipple construction has not been illustrated.

These sections are hollow to provide chambers 12 for a fluid which is heated for creating a circulation of either hot water, steam or vapor as the case may be. The sections 11 are shown as being vertically disposed although they may include horizontal sections of the conventional type.

A grate 15 is supported from the side walls of the furnace and thereby divides the main body of the furnace into a firebox 16 and an ash pit 40 17. The firebox is relatively deep so that the hot coals 18 will not only be in contact with a large surface area of the side walls of the furnace but a large heating surface will be presented to the hot gases of combustion.

A pair of hollow members 20 and 21 project from the side walls of the furnace and form the top of the firebox. These members are hollow to provide chambers 22 which are in communication with the chambers 12 in the side walls while the tops 23 of these members are flat. Their underfaces, as shown at 24, are curved to form the top wall of the firebox. The inner reduced ends 25 are spaced from each other to provide a central passage 26 which connects the firebox 16 55

with a flat elongated passage 27 below a header 28. This passage 26, as shown in Fig. 2, is progressively expanded from the front end to the rear end so that the wider portions of the passage are located in the reduced end 29 of the furnace and adjacent a flue 30.

A hollow dome 31 covers the top of the furnace and is in communication at its side edges with the vertical chambers 12 in the side walls of the furnace.

The header 28 is suspended from the dome 31 by means of elongated hollow hangers 35 whereby the header 28 is placed in communication with the dome 31 by means of the restricted passages 36. These hangers in connection with the upper surface 37 of the header 28 and the bottom wall of the dome 31 form a channel 39 which is connected with the flue 30 at its rear end while it is in communication with elongated chambers 40 formed by the header 28, the hangers 35 and the bottom wall of the dome 31. These passages 40 extend longitudinally of the furnace and are adapted to carry the hot gases of combustion from the flat passage 27 to the forward end of the exhaust channel 39.

It will be noted that the longitudinal side edges 41 of the header 28 are spaced from the side walls of the furnace to provide restricted passages 42 which extend longitudinally of the furnace but which converge towards each other at the rear end of the furnace.

A door 45 is hingely mounted at 46 on the front wall of the furnace and closes an opening 47 formed in the front wall 48 whereby the firebox 16 is charged with fuel.

While I have shown that the firebox in this instance is charged with coal it will be appreciated that either gas or oil may be utilized for fuel as is well known in the art.

It will be noted that the hangers 35 have their forward ends 50 spaced from the front wall 48 of the furnace to provide restricted passages 51 to permit the hot gases from the passages 40 to enter the longitudinal discharge channel 39.

In view of the fact that the furnace is triangular in horizontal section the header 28 will likewise be approximately triangular as will be the members 20 and 21. The grate 15 likewise will be substantially triangular with the wider portions of these members located at the front end of the furnace.

In this type of construction large heating surfaces are presented to the hot gases of combustion and to the flame or fuel in the firebox while a tortuous path is provided for the hot gases throughout the furnace in order to delay the passage of the gases whereby they will come in contact with the maximum heating surfaces for the fluids in the various coils or header.

At 60 is shown a section nipple. A number of the nipples are employed for placing the various sections of the dome in communication with each other.

I claim:

1. A furnace comprising a housing which is triangular in plan, a grate section, a top section above the grate and formed of members projecting towards each other from the side walls of the housing, the adjacent edges of said member being spaced from each other to provide a restricted passage for the hot products of combustion, a header for water located above the members and having the side edges spaced from the side walls of the housing to permit the products of combustion to pass around the edges, a dome for water, spaced channel members connecting the dome with the header and suspending the head from the dome, said channel members being spaced from the front wall of the housing and forming a discharge passage for the products of combustion.

water, spaced channel members connecting the dome with header and suspending the header from the dome, said channel members being spaced from the front wall of the housing and forming a discharge passage for the products of combustion.

2. A furnace comprising a housing which is triangular in plan, a grate section, a top section above the grate and formed of members projecting towards each other from the side walls of the housing, the adjacent edges of said member being spaced from each other to provide a restricted passage for the hot products of combustion, said passage being expanded from the front end to the rear end, a header for water located above the members and having the side edges spaced from the side walls of the housing to permit the products of combustion to pass around the edges, a dome for water, spaced channel members connecting the dome with the header and suspending the head from the dome, said channel members being spaced from the front wall of the housing and forming a discharge passage for the products of combustion.

3. A furnace comprising a housing which is triangular in plan, a grate section, a top section above the grate and formed of members projecting towards each other from the side walls of the housing, the adjacent edges of said members being spaced from each other to provide a restricted passage for the hot products of combustion, the passage extending centrally and throughout the length of the housing and being progressively expanded through the length thereof, a header for water located above the members and having the side edges spaced from the side walls of the housing to permit the products of combustion to pass around the edges, a dome for water, spaced channel members connecting the dome with the header and suspending the header from the dome, said channel members being spaced from the front wall of the housing and forming a discharge passage for the products of combustion.

4. A furnace comprising a housing which is triangular in horizontal section, a flue, a grate section, a hollow dome covering the top of the housing, a header suspended from the dome and having the side edges spaced from the side walls of the housing to provide passages for the products of combustion, spaced means for suspending the header and forming in connection with the header and dome a discharge passage for the products of combustion to the flue, hollow deflectors in communication with the header projecting towards each other from the side walls of the housing and located between the grate and the header, the walls of the housing including water chambers in communication with the header, dome and deflectors.

5. A furnace comprising a housing which is triangular in horizontal section, a flue at the rear end of the housing, a grate, a dome covering the top of the housing, deflectors extending from the side walls of the housing and having the adjacent edges spaced from each other to provide an elongated central passage for hot gases of combustion, a header, means suspending the header from the dome in spaced relation with the deflector, said header having the side edges spaced from the side walls of the housing to provide elongated passages, the suspension means forming a channel between the dome and header, said channel opening at the rear end thereof into the flue, the front end of the channel opening into the space above the header, said passages

and channel forming a tortuous path for the hot gases of combustion between the firebox and the flue.

6. A furnace comprising a housing which is triangular in horizontal section, a flue at the rear end of the housing, a grate, a dome covering the top of the housing, deflectors extending from the side walls of the housing and having the adjacent edges spaced from each other to provide an elongated central passage for hot gasses of combustion, a header, means suspending the header from the dome in spaced relation with the deflectors, said header having the side edges spaced from the side walls of the housing to provide elongated passages, the suspension means forming a channel between the dome and header, said channel opening at the rear end thereof into the flue, the front end of the channel opening into the space above the header, said passages and channel forming a tortuous path for the hot gases of combustion between the firebox and the flue.

7. A furnace comprising a housing which is triangular in horizontal section, a flue at the rear end of the housing, a grate, a dome covering the top of the housing, deflectors extending from the side walls of the housing and having the adjacent edges spaced from each other to provide an elongated central passage for hot gases of combustion, a header, means suspending the header from the dome in spaced relation with the deflector, said header having the side edges spaced from the side walls of the housing to provide elongated passages, the suspension means forming a channel between the dome and the header, said channel opening at the rear end thereof into the flue, the front end of the channel opening into the space above the header, said passages and channel forming a tortuous path for the hot gases of combustion between the firebox and the flue, the underfaces of the deflectors from the inner edges thereof being curved downwardly towards the side walls of the housing. 5 10 15 20
